Patented Aug. 14, 1917.

INVENTOR,
Henry Alberts
By David Lichtenstein
ATT'y.

UNITED STATES PATENT OFFICE.

HENRY ALBERTS, OF LYNN, MASSACHUSETTS.

INSOLE STRUCTURE.

1,236,528.

Specification of Letters Patent. Patented Aug. 14, 1917.

Application filed July 3, 1916. Serial No. 107,399.

To all whom it may concern:

Be it known that I, HENRY ALBERTS, a citizen of the United States, and resident of Lynn, in the county of Essex and State of Massachusetts, have invented a new and useful Improvement in Insole Structures, of which the following description, in connection with the accompanying sheet of drawing, is a specification.

This invention has for its object the production of a reinforced semi-flexible insole for shoes, and is specially provided with a reinforcing element in the forepart thereof which permits the same to be flexible lengthwise at the ball of the foot where flexibility is required, and at the same time stiffens that portion of the insole against being flexible crosswise;—it being a known fact in the trade, that the ordinary types of flexible insoles, which are flexible crosswise as well as lengthwise at the ball portion thereof, are very troublesome to handle and manipulate in the manufacture of shoes containing same, especially in the so-called McKay shoes, where the upper is pulled over the edge of the insole and secured thereto by temporary means (as by tacks for example). The pulling over of the edge of the upper on the flexible ball part of the ordinary flexible insole, causes the same to puff up, wrinkle, and to become otherwise distorted, because of the fact that the same is made up without stiffening crosswise, to resist the pressure applied thereto in the pulling over of the upper thereon. Again, more or less trouble is encountered in using the ordinary types of flexible insoles because the edges thereof are too delicate and weak to hold and clench the tacks used for holding the upper edges secured thereto in the McKay shoes.

To provide an insole which has body thereto to overcome the aforesaid objectionable features found common in the ordinary types of flexible insoles, which will permit flexibility lengthwise and resist flexibility crosswise, and which may be manufactured at the lowest cost, is the object of my invention.

To these as well as other ends, my invention consists of the novel features of construction, combination and arrangement of parts described in the following specification, and particularly pointed out in the subjoined claims.

Referring to the drawing—

55

Figure 1 represents a plan view of the insole embodying my invention.

Fig. 2 represents a sectional view taken on line 2—2 in Fig. 1.

Fig. 3 represents a section taken on line 60 3—3 in Fig. 1.

Fig. 4 represents a plan view of the slotted reinforcing and stiffening member, having a toe part made integral therewith.

Fig. 5 represents the same view as Fig. 4, 65 but indicates the use of a separate toe part and an intermediate slotted reinforcing and stiffening member.

Fig. 6 represents a perspective view of a flexible insole of my type, showing the same 70 supplied with the toe-type of reinforcing and stiffening member.

Fig. 7 represents the same view as Fig. 6, but shows an intermediate type of reinforcing and stiffening member, similar to that 75 shown in Fig. 5.

Fig. 8 represents a modified view of a part of the forepart of an insole, showing the same made up of but two layers—the upper layer being an ordinary layer of flexible 80 material, and the lower layer being a slotted layer of stiffening material.

Like numerals refer to like parts throughout the several views of the drawing.

The numeral 1 represents a stiffening 85 shank-piece which may be made of sole leather of any desired degree of stiffness, or other suitable material, forming the heel 2 and preferably the arch 3 which terminates at 4 toward the ball of the foot. 5 in its entirety, represents the ball portion or forepart of the insole, having the toe-portion 6 and the engaging end 7, which is glued, stitched, or otherwise suitably secured to the end 4 of the shank-piece 1,—the joining ends 90 of the shank-piece 1 and the ball portion or forepart 5 of the insole being preferably skived and glued, stitched, or otherwise suitably secured and united together to form a complete unit sole.

100

8 represents an upper layer of the ball portion or forepart of the insole, which may be made up of felt, fabric, upper leather, or any other suitable flexible material (preferably the latter). 9 represents the lower layer 105 of the ball portion or forepart of the insole which is similar in shape to that of the upper layer 8 and which may also be made of

fabric, canvass, upper leather, felt, or other suitable flexible material (preferably fabric). Between the layers 8 and 9 of the fabric is inserted the slitted-stiffening-member 10 which is provided with a series of crosswise slits 11, which are preferably cut completely through, with the ends 12 thereof terminating at an appreciable distance from the edge of the stiffening-member 10, as indicated in Fig. 5. The slitted-stiffening-member 10 (Figs. 5 and 7) may terminate at 13, instead of reaching to the tip of the toe of the insole for including the integral toe-piece 14, as shown in Fig. 4,—said stiffening-member 10 being made of buckram, or other fabric, leather, felt, or any other suitable stiffening material. 15 represents a separate stiffening-toe-piece which may be used with the toeless type of slitted-stiffening-member 10, shown in Figs. 5 and 7, and may be made of any suitable stiffening material, such as buckram, leather, fiber, etc., said stiffening toe-piece 15 being also preferably used in connection with the integral toe type of slitted stiffening-member 10, shown in Figs. 4 and 6, as indicated by 15^a,—stiffened leather being the most practicable, however, since the steaming process employed in shaping and setting the toe-cap of the upper of the shoe, when the same is first stretched over the last, usually affects the toe-portion of the insole and softens the same, especially when relying upon buckram, felt, or other such material for toe stiffening purposes. The steaming process is often found to weaken the toe-portion of the insole of flexible insoles, and even damages the same to a degree where it becomes useless. For that reason, I propose to preferably use a stiffening-toe-member which will not readily be affected by said steaming process; and suggest, when using the integral toe type of reinforcing and slitted-stiffening-member 10 shown in Figs. 4 and 6, (when the same is made of buckram, felt, or the like) to employ along with the same an auxiliary stiffening-toe-piece as 15^a, which may be made of stiff leather for overcoming the effect produced by the steaming process, when relying upon buckram, fabric, or the like,—it being understood, however, that the slitted stiffening-member 10 may be made of leather with an appreciable degree of stiffness, which, by virtue of the slits 11 cut therein, produces the lengthwise flexibility for the forepart that is necessary, in which event, no extra stiffening-toe-piece 15^a will be required to be incorporated in the insole.

60 The slitted-stiffening-member 10 with the toe-stiffening-piece 15 or 15^a are sandwiched in between the upper layer 8 and the lower layer 9 of the forepart, and are secured in place therewith by any suitable means, as 65 by stitching or by the use of adhesives (preferably the latter); it being understood that the adjacent surfaces of the upper and lower layers of the forepart may be gummed or cemented, or otherwise suitably treated, if desired, for securing the reinforcing element 70 in working position therewith.

It may be observed that while I have shown the ball portion or forepart of the insole using the reinforcing-slitted-member sandwiched between an upper and lower 75 flexible forepart layer, I do not wish to be limited against using a ball portion or forepart for the insole in which the slitted-stiffening-element makes up the lower-ply of the ball portion of the insole and is covered by 80 and secured to a flexible layer which makes up the upper-ply of the ball portion, as shown in Fig. 8; thus furnishing a two-ply ball portion for the insole instead of the three-ply shown in Figs. 6 and 7.

It may further be observed, in connection with the two-ply type of ball portion, indicated in Fig. 8, that if desired, the slitted layer may be made of buckram, or other suitable stiffening material, and reinforced 90 at the toe-portion thereof with a stiffened toe-piece between same and the upper layer in a similar manner to that indicated in Fig. 6.

It may also be observed that according to 95 the degree of stiffness of the stiffening-member 10, the slits 11 may be spaced to suit conditions; and also that, depending upon the degree of stiffness of said stiffening-member, the slits 11 may be cut and made of any desired width necessary (from the width of a knife cut up) to provide ample flexibility for the same.

While the preferred embodiments of my 10 invention have been described in detail, it will be understood that I do not wish to be limited to the particular construction set forth, since various changes in the form, material, proportions, and arrangement of parts and in the details of construction may 11 be resorted to without departing from the spirit and scope of the invention, or destroying any of the advantages contained in the same, heretofore described and defined in the subjoined claims.

What I claim is:

1. An insole comprising a relatively stiff heel and shank section terminating in the rear of the ball line; a forepart of material inherently more flexible than that of the heel and shank section, and secured to the forward end thereof; and a layer of reinforcing material under the forepart, transversely slitted adjacent the ball line and unslitted at the toe portion, the slits terminating short of the sides of the insole, and the reinforcing layer being secured throughout its area to the forepart.

2. An insole comprising a relatively stiff heel and shank section terminating in the

5 rear of the ball line, a forepart of material inherently more flexible than that of the heel and shank section and secured to the forward end thereof, a layer of reinforcing material under the forepart, transversely slitted adjacent the ball line and unslit at the toe portion, the slits terminating short of the sides of the insole, and the reinforcing layer being secured throughout its area to the forepart, and a covering layer of flexible material similar in shape to said fore-

10 part, adapted to sandwich said reinforcing layer with said forepart, being adhesively secured to said reinforcing layer throughout its area and joined to the under side of said heel and shank sections at the forward end thereof.

HENRY ALBERTS.
